mesne assignments, to Philco Radio and Tele-
vision Corporation, Philadelphia, Pa., a corpo-
ration of Delaware

Application December 19, 1936, Serial No. 116,803
In Great Britain August 4, 1936

19 Claims. (Cl. 179—171)

This invention relates to improvements in radio amplifier circuits and, more particularly, to a novel degenerative combined detector and audio amplifier system which may be used, for example, in a radio receiver, public address system, or the like, wherein it is desired to amplify the audio frequency signals with a minimum of distortion.

The principal object of the invention is to provide an improved system of this class embodying certain novel features or characteristics as set forth hereinafter in greater detail.

A more specific object of the invention is to provide novel means for biasing the detector in a system of this type which eliminates the necessity of providing a relatively expensive filter condenser and, at the same time, enables the minimizing of hum voltages introduced in the signal channel through the detector plate circuit.

Another object of the invention is to provide a novel tone control by means of which a selected portion of the audio frequency band may be augmented or diminished by variation of the amount of degeneration or regeneration of the selected signal.

A further object of the invention is to provide novel means for varying the amount of degeneration of the lower frequencies, which variation may be effected simultaneously with the volume adjustment, to thus vary the relative proportion of bass note reproduction.

Other objects and features of the system will be apparent from the following description and the accompanying drawing, the single figure of which illustrates a combined detector and audio amplifier system which may form part of a radio receiving system. It will be understood, of course, that the invention is not limited to the specific system illustrated but is capable of use in any radio receiver or other system employing an audio frequency amplifier and signal utilization means. Certain features of the invention may be employed, for example in a simple amplifier circuit in which there is no detector or demodulator.

Referring to the drawing, there is shown a diode-triode tube V₁, the diode elements of which are adapted to function as a detector and may be supplied with modulated carrier-wave signals by means of the tuned transformer T₁. Such signals may be supplied from any suitable source, as represented by the source E. This signal source may, for example, represent the portion of a superheterodyne radio receiver preceding the second detector. Load resistors R₁ and R₂ are provided in the circuit of the diode rectifier and

there are also provided radio frequency by-pass condensers C₁ and C₂ which are connected to ground as illustrated. It will be apparent that rectified audio frequency signals will build up across the load circuit comprising these elements.

5 A potentiometer P₁ may be connected to the resistor R₂ through coupling condenser C₃ as illustrated, the opposite side of the potentiometer being connected to ground. This potentiometer 10 serves as a volume control and functions to transfer a desired portion of the rectified audio frequency signal to the control element or grid of tube V₁ which functions both as a detector and as an amplifier as well understood. It will be 15 apparent that the signals appearing across the tapped portion of the potentiometer P₁, plus any other signals which may be established between the cathode of tube V₁ and ground, will be supplied to the control element of the tube.

The output of the tube V₁ is obtained across the anode load resistor R₃ and is thence transferred by means of the coupling condenser C₄ and resistor R₄ to an amplifier tube V₂, the output of which is supplied through an output transformer T₂ to any suitable signal utilization means such as the loud speaker LS. The tube V₂ may be a pentode as illustrated or any other suitable power output tube and may, if desired, be self-biased by means of the resistor R₅ and associated condenser C₅ connected in the cathode lead of the tube as illustrated. The condenser C₆ shunted across the primary winding of the transformer T₂ serves to by-pass signals of very high frequency and also serves to vary the phase 30 of such signals to some degree.

A portion of the output signal from the secondary of transformer T₂ may be supplied through a coupling condenser C₇ to a potentiometer P₂ comprising two resistors R and R₇. 40 The movable arm of the potentiometer P₂ is adapted to move over both of the resistors R₆ and R₇. One end of the resistor R₇ may be grounded and the cathode of tube V₁ may be connected to the common point of resistors R₆ and R₇ as illustrated. The movable potentiometer arm is connected through a condenser C₈ to the cathode lead as illustrated for a purpose which will be explained later. A condenser C₉, whose purpose will also be explained later, is connected in shunt relation with the resistor R₇.

By means of this arrangement, a portion of the signal in the output circuit of the system may be returned to the input of the amplifier system in a manner to cause the amplifier system to be degenerative. In other words, the potentiometer 50 55

P_2 is connected to the transformer T_2 in such a manner as to effect feed-back of a signal which serves to decrease the output signal of the system. By virtue of the degenerative connection of the feed-back arrangement, any signal distortion incurred in the amplifier channel will be materially diminished.

It is to be noted further that this system effects simultaneous variation of volume and degeneration in inverse relation to one another whenever potentiometer P_1 is actuated. In addition to the degenerative or negative feed-back connection from potentiometer P_2 to the cathode of V_1 , there is a regenerative or positive feed-back connection extending from potentiometer P_2 to the control grid of tube V_1 . This connection extends through the resistor R_2 and the coupling condenser C_3 to the ungrounded end of potentiometer P_1 . This positive feed-back path is supplemented by a path in parallel with resistor R_2 , which includes the diode elements of tube V_1 , the secondary winding of transformer T_1 , and the resistor R_1 . Whenever potentiometer P_1 is actuated, the positive feed-back voltage is varied in direct relation to the signal applied to the grid of tube V_1 , and hence the over-all negative feed-back voltage is varied in inverse relation to the applied signal.

Considering the impedance relations involved, generally speaking, the loud speaker will have a very low impedance of the order of 1 or 2 ohms, while the potentiometer P_2 may have an impedance of the order of 1000 or 2000 ohms and, consequently, it will not cause any appreciable load on the output circuit. On the other hand, the impedance associated with the tube V_1 may be of the order of 100,000 ohms and, therefore, with respect to the tube V_1 , the resistor R_7 may be considered to be a source of signals having substantially zero impedance.

Variations in the frequency response of the amplifier system may be obtained by varying the amount of degeneration of signals of the different frequencies and, in fact, under certain conditions, the amplifier system may be made regenerative in order to increase the response at certain frequencies. By suitably proportioning the respective circuit constants, this result may be obtained without affecting the stability of the circuit. For example, the condenser C_7 will tend to reduce the amount of degeneration for those frequencies at which its impedance is comparable to the combined impedance of resistors R_8 and R_7 . At such frequencies, the feed-back signal which is set up across the resistor R_7 is a relatively small proportion of the total feed-back signal and, therefore, the amount of degeneration of the system is materially less than that obtaining for frequencies at which the impedance of condenser C_7 is small or negligible in comparison to the combined impedance of resistors R_8 and R_7 . It will be seen, therefore, that the condenser C_7 may be utilized to provide bass compensation by designing this condenser so that it has an impedance comparable to the impedance of potentiometer P_2 for signals of those frequencies which it is desired to augment.

The condenser C_8 may be utilized to decrease the high frequency response of the amplifier system when the potentiometer control arm is on the resistance R_8 . For normal signal feed-back, the potentiometer arm will be positioned at the common point of the two resistors R_8 and R_7 and, therefore, when the potentiometer arm is on the 75

resistance R_8 , the signal feed-back will be greater than normal. On the other hand, when the potentiometer arm is on the resistance R_7 , the signal feed-back will be less than normal.

5 The resistance R_7 will be small in comparison to the other resistors of the circuit of tube V_1 and, therefore, no degeneration will occur in the tube V_1 and its associated circuits other than the degenerative action of the system as a whole. Therefore, maximum gain is obtained from the amplifier portion of the tube V_1 . In order to provide adequate bias for the control element of tube V_1 , however, there is provided a resistance R_8 which is connected between the high potential side of the power supply circuit and the resistor R_7 . In this manner, a unidirectional current is caused to flow through resistor R_7 which sets up a unidirectional voltage across this resistor, providing a suitable bias for the control element of tube V_1 . This arrangement serves an additional important function in that it enables complete balancing out or bucking of hum signals. By connecting the resistor R_8 to a suitable point on the power supply unit as illustrated and by properly 10 designing the several circuit constants, complete hum bucking action may be obtained. It will be seen that the ripple voltage in the power supply unit, which is inherently present due to the filtering action of the filter, is applied to the grid circuit of tube V_1 through resistors R_8 and R_7 and is also applied to the plate of tube V_1 through resistors R_9 and R_{10} . Moreover, it will be apparent that the phase of the signals applied to these two 15 elements of tube V_1 will be the same. Due to the phase reversal which takes place in the tube V_1 , the hum signal supplied to the grid circuit of the tube may be made to balance or buck out the hum signal supplied to the plate circuit of the tube. This action obtains when the ratio of the 20 hum signal across resistor R_7 to the hum signal built up across resistor R_8 is equal to the amplification or gain of the tube V_1 and when the two signals are alike in phase. The phase relation 25 of these two signals may be controlled by proper design of the values of R_8 , R_7 , R_9 and R_{10} and the condensers C_9 and C_{10} . By suitable design of these circuit constants, substantially complete 30 hum elimination may be obtained.

It may now be noted that the condenser C_9 may be a relatively small condenser which serves to control the phase of the hum signal across resistor R_7 rather than to prevent the formation of a hum signal across this resistor. This condenser replaces a relatively large and costly filter condenser which has been used in self-biasing arrangements. In this respect, the present invention effects an economy which is important in present day mass production.

The power supply unit may comprise a transformer T_3 , a rectifier V_3 and a conventional filter including shunt condensers C_{11} and C_{12} and a series choke coil L . The resistor R_{10} may be used to supply other tubes of the system.

In a specific system by means of which the results set forth above were obtained, the following circuit constants were employed:

$R_1 = 50,000$ ohms	$C_1 = 110$ micro-microfarads
$R_2 = 330,000$ ohms	$C_2 = 110$ micro-microfarads
$R_3 = 250,000$ ohms	$C_3 = 1250$ micro-microfarads
$R_4 = 1$ megohm	$C_7 = .25$ microfarad
$R_5 = 1,400$ ohms	$C_8 = .15$ microfarad
$R_6 = 600$ ohms	$C_9 = .05$ microfarad
$R_8 = 190,000$ ohms	$C_{10} = .16$ microfarads
$R_9 = 3,300$ ohms	$P_1 = 2.0$ megohms
$R_{10} = 75,000$ ohms	$E_1 = 245$ volts
	$E_2 = 210$ volts

The tube V_1 may be a 75 type diode-triode tube, while the tube V_2 may be a 6F6 type tube. The power supply unit may be adapted to operate from a 60 cycle A. C. source.

From the above description and the accompanying illustration, it will be seen that the invention provides a novel degenerative circuit by means of which signal distortion may be kept at a very low level and variation in frequency response may be obtained by varying the amount of degeneration. Moreover, the invention provides novel means for obtaining both base compensation and high frequency compensation. While either of these may be fixed or variable, the arrangement illustrated enabling variation of the high frequency compensation is particularly desirable. The invention provides further a simple and convenient method of eliminating hum while, at the same time, providing a suitable bias for the input tube of the regenerative system.

It will be understood, of course, that the invention is not limited to the specific system illustrated but is capable of various changes and modifications without departing from its scope.

I claim:

1. In a signal amplifying device having an input circuit and an output circuit, said device including a space discharge device having grid and cathode electrodes connected to said input circuit, a potentiometer, a manually adjustable contact on said potentiometer, means connecting said potentiometer in shunt with said output circuit, a fixed intermediate tap on said potentiometer, means connecting one of said electrodes to said fixed intermediate tap whereby a portion of said potentiometer is included in said input circuit, and a connection including a reactance between said fixed tap and said adjustable contact, whereby the frequency response of said device may be varied by positioning said adjustable contact in relation to said fixed tap.

2. In a signal amplifying device having an input circuit and an output circuit, said device including a space discharge device having a grid and a cathode connected to said input circuit, a potentiometer, a manually adjustable contact on said potentiometer, means connecting said potentiometer in shunt with said output circuit, a fixed intermediate tap on said potentiometer, means connecting said cathode to said fixed intermediate tap whereby a portion of said potentiometer is included in said input circuit, and a connection including a reactance between said fixed tap and said adjustable contact, whereby the frequency response of said device may be varied by positioning said adjustable contact in relation to said fixed tap.

3. In a signal amplifying device having an input circuit and an output circuit, said device including a space discharge device having a grid and a cathode, connected to said input circuit, a potentiometer, a manually adjustable contact on said potentiometer, means including a condenser connecting said potentiometer in shunt with said output circuit, a fixed intermediate tap on said potentiometer, means connecting said cathode to said fixed intermediate tap whereby a portion of said potentiometer is serially included in said input circuit, and a connection including a second condenser between said fixed tap and said adjustable contact.

4. In a signal amplifying device having an input circuit and an output circuit, said device including a space discharge device having a grid and a cathode connected to said input circuit, a

25 5. In a signal amplifying device having an input circuit and an output circuit, said device including a space discharge device having a grid and a cathode connected to said input circuit, a potentiometer, a manually adjustable contact on said potentiometer, means connecting said potentiometer in shunt with said output circuit, a fixed intermediate tap on said potentiometer, means connecting said cathode to said fixed intermediate tap whereby a portion of said potentiometer is serially included in said input circuit, and a connection including a second condenser between said fixed tap and said adjustable contact, the reactance of said second condenser being so related to the reactance of the first-mentioned condenser and the resistance of said potentiometer, that the degeneration of high audio frequencies increases as said adjustable contact is moved toward said first-mentioned condenser.

50 6. In an audio frequency amplifier having an input circuit and an output circuit, said amplifier including a space discharge device having a grid and a cathode connected to said input circuit, a potentiometer, a manually adjustable contact on said potentiometer, means including a condenser connecting said potentiometer in shunt with said output circuit, a fixed intermediate tap on said potentiometer, means connecting said cathode to said fixed intermediate tap whereby a portion of said potentiometer is serially included in said input circuit, and a connection including a second condenser between said fixed tap and said adjustable contact, the reactance of said second condenser being so related to the reactance of the first-mentioned condenser and the resistance of said potentiometer, that the degeneration of high audio frequencies increases as said adjustable contact is moved toward said first-mentioned condenser.

55 7. In a signal amplifying device having an input circuit and an output circuit, said device including a space discharge device having grid and cathode electrodes connected to said input circuit, a potentiometer, a manually adjustable contact on said potentiometer, means connecting said potentiometer in shunt with said output circuit, a fixed intermediate tap on said potentiometer, said intermediate tap lying between the outer limits of movement of said adjustable contact, means connecting one of said electrodes to said fixed intermediate tap whereby a portion of said potentiometer is included in said input circuit, and a connection including a reactance between said fixed tap and said adjustable contact, whereby the frequency response of said device may be varied by positioning said adjustable contact in relation to said fixed tap.

60 8. In a signal amplifying device having an input circuit and an output circuit, said device including a space discharge device having a grid and a cathode connected to said input circuit, a potentiometer, a manually adjustable contact on said potentiometer, means including a con-

denser connecting said potentiometer in shunt with said output circuit, a fixed intermediate tap on said potentiometer, said intermediate tap lying between the outer limits of movement of said adjustable contact, means connecting said cathode to said fixed intermediate tap whereby a portion of said potentiometer is serially included in said input circuit, a connection including a second condenser between said fixed tap and said adjustable contact, and a third condenser connected between said fixed tap and one side of said output circuit.

9. In an audio frequency amplifier having an input circuit and an output circuit, said amplifier including a space discharge device having a grid and a cathode connected to said input circuit, a potentiometer, a manually adjustable contact on said potentiometer, means including a condenser connecting said potentiometer in shunt with said output circuit, a fixed intermediate tap on said potentiometer, said intermediate tap lying between the outer limits of movement of said adjustable contact, means connecting said cathode to said fixed intermediate tap whereby a portion of said potentiometer is serially included in said input circuit, and a connection including a second condenser between said fixed tap and said adjustable contact, the reactance of said second condenser being so related to the reactance of the first-mentioned condenser and the resistance of said potentiometer, that the degeneration of high audio frequencies increases as said adjustable contact is moved toward said first-mentioned condenser.

10. In an audio amplifying system, an audio channel including at least one space discharge device having an input circuit, means for supplying an input signal to said input circuit, a degenerative connection from said audio channel to said input circuit for supplying a degenerative control signal to the input circuit, and means for simultaneously varying the amplitude of the input signal and the amplitude of the degenerative control signal in inverse relation to one another.

11. An audio frequency amplifier system comprising an electron discharge amplifier having an anode, a cathode and a grid, means for supplying a signal to be amplified, a potentiometer connected in circuit with said signal supplying means and having its arm connected with said grid, a resistor connected between the low potential end of said potentiometer and said cathode, and means connected across said resistor for supplying thereto a feed back voltage controlled by the current in the anode-cathode circuit.

12. In an audio signal voltage transmission system, a source of audio signal voltage, an audio amplifier having input and output circuits, means for controlling the magnitude of the said voltage impressed on said input circuit, an audio signal voltage feed back circuit between the amplifier output circuit and input circuit for feeding back signal voltage in degenerative phase, and a second feed back circuit for feeding back signal voltage in regenerative phase, said controlling means being included in one of said feed back circuits thereby simultaneously to control the magnitude of one of said feed back voltages.

13. In an audio amplifying system, an audio amplifier having an input circuit and an output circuit, an audio channel connected to said output circuit, a gain control potentiometer connected in said input circuit to vary the input sig-

nal applied thereto, and a degenerative connection from said audio channel to a predetermined intermediate tap point on said potentiometer for supplying to said input circuit a degenerative control signal whose amplitude varies in inverse relation to the amplitude of the input signal over at least a portion of the adjustment range of said gain control potentiometer.

14. An audio frequency amplifier system comprising an electron discharge amplifier having an input circuit and a fixed resistance output circuit, a potentiometer and a resistor connected to be traversed in series by the signal to be amplified, means connecting said resistor and the adjacent adjustable portion of said potentiometer in said input circuit, and means for applying across said resistor a feedback voltage in accordance with the current in said output circuit.

15. An audio frequency amplifier system comprising an electron discharge amplifier having an input circuit and an output circuit, means for supplying a signal voltage to be amplified, means separate from and controlled by said output circuit for producing a feedback voltage, and a device connected with said signal voltage supplying means, with said feedback voltage producing means and with said input circuit for simultaneously increasing the proportion of signal voltage applied to the input circuit and decreasing the proportion of feedback voltage supplied thereto, and said feedback voltage means being constructed to have a frequency discriminating characteristic.

16. An audio frequency amplifier system comprising an electron discharge amplifier having an input circuit and an output circuit, means for supplying a signal voltage to be amplified, means separate from and controlled by said output circuit for producing a feed-back voltage, and a device connected with said signal voltage supplying means, with said feed-back voltage producing means and with said input circuit for simultaneously increasing the proportion of signal voltage applied to the input circuit and decreasing the proportion of feed-back voltage supplied thereto.

17. An audio frequency amplifier system comprising an electron discharge amplifier having an input circuit and an output circuit, the resistance of the output circuit being fixed, means for supplying a signal voltage to be amplified, means for supplying a feed-back voltage controlled by the current in said output circuit, and a device connected with said signal voltage supplying means, with said feed-back voltage supplying means and with said input circuit for simultaneously increasing the proportion of signal voltage applied to the input circuit and decreasing the proportion of feed-back voltage supplied thereto.

18. In a radio receiver, a source of audio signals, an audio amplifier having an input circuit and an output circuit, a volume control device connected to said source and connecting said input circuit to said output circuit degeneratively for transferring to said input circuit controllable portions of the signal in said output circuit and the signal from said source, said degeneratively connected volume control device including means for varying the said portions of said signals in such manner that the degenerative signal increases from a relatively low value to a maximum value as the volume control is progressively adjusted to decrease the output level from a maximum value to a low value.

19. In an audio amplifying system, an audio

amplifier having an input circuit and an output circuit, means for supplying signal energy to said input circuit, a potentiometer connected to said input circuit for varying the amplitude of signals supplied to the amplifier, means for deriving a voltage from said output circuit and for applying said voltage regeneratively to said potentiometer,

5 eter, and means for deriving another voltage from said output circuit and for applying said voltage degeneratively to said input circuit, to thereby apply to said input circuit a resultant degenerative voltage whose magnitude varies inversely with the magnitude of the input signal.
